(57) **CLAIM**

The ornamental design for a multipurpose divot tool as shown and described.

DESCRIPTION

FIG. 1 is a front perspective view of a multipurpose divot tool showing our new claimed design.

FIG. 2 is a back perspective view thereof;

FIG. 3 is a left-side elevational view, the right-side elevational view being a mirror image thereof;

FIG. 4 is a back elevational view thereof;

FIG. 5 is a front elevational view thereof;

FIG. 6 is a top plan view thereof; and,

FIG. 7 is a bottom plan view thereof.

The broken lines in the figures show portions of the multipurpose divot tool that form no part of the claimed design.
